UNITED STATES PATENT OFFICE.

EUGENE C. HEILHECKER, OF BRISTOL, RHODE ISLAND, ASSIGNOR TO NATIONAL INDIA RUBBER COMPANY, A CORPORATION OF RHODE ISLAND.

HEEL CONSTRUCTION FOR FOOTWEAR.

Application filed January 14, 1921. Serial No. 437,159.

To all whom it may concern:

Be it known that I, EUGENE C. HEILHECKER, a citizen of the United States, residing at Bristol, in the county of Bristol 5 and State of Rhode Island, have invented certain new and useful Improvements in Heel Constructions for Footwear, of which the following is a full, clear, and exact description.

10 This invention relates to a heel construction for footwear, and more particularly to a construction in which a heel of vulcanizable material is attached by vulcanization to the body of a shoe or other article of foot- 15 wear.

In the footwear art heels of vulcanizable material which are attached by vulcanization to the footwear article are subjected to considerable hard usage, tending to loosen 20 them from the body of the article, and to avoid this difficulty it has been common to provide the heel with an upstanding flange around its sides and rear for attachment to the lower part of the heel portion of the 25 shoe or other article. Prior to my invention this upstanding flange was tapered to a feather edge, which construction is defective in several particulars and presents some manufacturing difficulties. In molding the 30 heel there is difficulty in completely filling the mold at the feather edge portion of the flange, and this edge is frequently torn either in removing the heel from the mold or while assembling the heel on a shoe. In addition the heel is semi-cured during the 35 molding operation, and during the final vulcanization after it is attached to the shoe the feather edge portion of the flange sometimes becomes overcured, and tends to crack 40 and pull away from the shoe body during use. These heels also are ordinarily made with a diverging taper from their bottom portion to the top, and hence the upstanding flange after attachment to the shoe does not 45 have a direct bearing on the heel body but overhangs the edge of the latter. Therefore in use, when the weight of the wearer is put upon the shoe, the upstanding flange tends to buckle outwardly and pull away from the 50 shoe body. An example of this overhanging flange construction is shown in patent to Whitney, No. 299,890 June 3, 1884.

Prior to my invention the shoe sole has ordinarily been either extended all the way 55 back over the heel, which causes a waste of

rubber stock, or its rear edge has been inserted in a recess formed at the breast of the heel, which recess has been made of a uniform depth, which does not provide a strong bond between the sole and heel. 60

An object of my invention is to provide a neat, strongly secured heel construction for vulcanizable footwear.

Another object is to provide an improved and strengthened connection between the 65 vulcanizable heel and sole members of a footwear article.

Still another object is to provide a heel of vulcanizable material which is simple and economical of manufacture and which affords a maximum of attaching surface while at the same time being sturdy in construction and not liable to injury during manufacture or attachment. 70

For a detailed disclosure of the invention 75 reference is had to the accompanying specification and drawings in which latter:

Fig. 1 is an elevation of the rear portion of a shoe embodying my invention;

Fig. 2 is a vertical longitudinal section of 80 the heel portion of a shoe with the various parts thereof broken apart; and

Fig. 3 is a perspective of my improved heel.

The numeral 1 represents the upper of a 85 shoe, which in the present instance is formed of canvas. Within the heel portion of the shoe is a composite counter formed of a piece of rag stock 2 and fabric 3. A wear piece 4 of canvas or other suitable material is disposed on the inside of the shoe, below which is the insole 5 of fibre or other suitable material. Below the insole is a composite shank stiffener 6 formed by a piece of fibre 7 and a strip of frictioned duck 8. 90 The space within the inturned edge of the upper is filled by a rag sole 9, a binder strip 10 of friction stock being laid over the joint. Below the filler sole 9 is a reinforcement 11 of friction stock and around the inturned 100 edge of the upper a foxing strip 12 is applied. An outsole 13 is rolled on and secured at its edge to the foxing 12 in the usual manner, said outsole terminating a short distance within the breast of the heel 14. The 105 heel is provided around its sides and rear with an upstanding tapered flange 15, which flange is abruptly truncated just short of a feather edge, as shown at 16. Adjacent the breast of the heel its upper surface is pro- 110

vided with a recess 17 for the reception of the rear end of the sole, this recess being rearwardly inclined, as shown in Fig. 2. To aid in the attachment of the heel its upper surface is knurled or otherwise roughened, as shown at 18, and nail holes 19 of the usual form and arrangement are provided for the reception of nails 20 which are shown as driven up through the heel in Fig. 3 to disclose their position. In the making of rubber footwear having canvas uppers and rubber heels which extend up over the heel portion of the upper the use of a foxing strip is desirable for the following reasons:—The heels as before pointed out are semi-cured during the molding operation, and it is difficult to secure a satisfactory union between such heels and the canvas of the upper, as the heel is no longer plastic and it therefore cannot be rolled into the interstices of the fabric. By the use of a foxing strip, however, which latter is of course made of unvulcanized material, the foxing after cementing can be thoroughly rolled into the fabric and is more securely united thereto during vulcanization than the semi-cured heel would be in the final cure. At the same time the semi-cured heel can be much more firmly secured to the rubber of the foxing during the curing operation than it could be to the canvas upper.

It will be seen that by my invention a sturdy heel construction is provided which can be securely attached to the shoe or other article, the tapering upwardly extending flange 15 giving a greatly increased attaching surface, while by terminating said flange short of a feather edge it can be readily molded, will not tear during removal from the mold or assembling of a shoe, and is not liable to overcure. The knurling or roughening 18 aids materially in securing the heel to the shoe by cementation, and the recess 17, with its inclined and roughened bottom, firmly grips the rear end of the sole, which cannot be detached from the heel by ordinary usage. It will be noted that the outer wall of the extending flange 15 forms a vertical continuation of the outer wall of the heel, hence, when the weight of the wearer is put upon the heel during usage there is no tendency of the flange 15 to buckle outwardly. Also by the slight reduction in the height of the flange 15 its truncated edge 16 forms in effect a continuation of the upper edge line of the outsole, as shown in Fig. 1, thereby adding to the neatness of the shoe.

Having thus described my invention, what I claim and desire to protect by Letters

60 Patent is:

1. An article of footwear comprising an upper, a sole, and a heel of vulcanized material united to said upper by a thin layer of vulcanized rubber, said heel having a substantially vertical upstanding flange curved

on its inner side to conform to the heel portion of the upper, said flange terminating in a thin truncated edge.

2. An article of footwear comprising an upper, a sole, and a heel of vulcanized material connected to said upper and sole by vulcanization, said heel having a tapering truncated edge connecting flange extending above its upper surface, the outer wall of said flange forming a vertical continuation 75 of the edge of the heel.

3. An article of footwear comprising an upper, and a sole, a foxing and a heel of vulcanized material united to said upper by vulcanization, said heel having a tapering 80 truncated edge flange extending above its upper surface around its sides and rear and connected to said foxing, said heel also having an inclined bottom sole receiving recess 85 at its breast.

4. An article of footwear comprising an upper, a foxing of vulcanized material extending around the same, an outsole of vulcanized material joined at its edge to said foxing, and a heel of vulcanized material overlapping at its breast the rear end of the outsole and having a truncated edge extension of its outer wall joined to said foxing, said truncated edge forming a continuation 90 of the upper line of the outsole edge. 95

5. An article of footwear comprising an upper, insole and filler sole, a foxing of vulcanized material extending entirely around the lower portion of the upper, a heel of vulcanized material having its side and rear 100 walls extended upwardly above its body, said extended walls being joined to the foxing and terminating in a relatively thin truncated edge below the top of the foxing, and an outsole of vulcanized material joined 105 at its edge to said foxing, the rear portion of said outsole being extended within the breast of the heel with the upper line of its edge in alignment with said truncated edge.

6. A shoe comprising an upper, insole and filler sole, a foxing of vulcanized material extending entirely around the lower portion of the upper, an outsole of vulcanized material joined at its edge to said foxing, and a heel of vulcanized material having a dished 110 upper surface interfitting with and joined to the heel portion of said upper, insole and filler sole, said upper surface adjacent the breast of the heel having an inclined-bottom recessed portion interfitting with and joined 115 to the rear end of the outsole, and an upstanding flange on the sides and rear of the heel joined to said foxing and having a truncated upper edge disposed on said foxing in alignment with and forming a continuation 120 of the upper line of the sole edge. 125

7. A molded partly cured rubber heel for integral attachment to footwear by vulcanization, comprising a heel body having a dished upper surface forming an integral 130

upstanding tapering flange around its rear and side edges, said flange terminating abruptly just short of a feather edge, and a sole receiving depression extending inwardly from the breast of the heel and inclined downwardly.

8. A partly cured rubber heel for attachment to footwear by nailing and vulcanization and comprising a heel body having an upper surface adapted to contact with and be connected to the heel portion of a shoe body, the heel body having an upwardly extending tapered flange with a truncated

upper edge, the inner wall of said flange being curved for connection with the lower 15 curved side and rear portions of the shoe counter, the outer wall of the flange forming a vertical continuation of the side and rear walls of the heel body, and the upper surface of the heel body adjacent the breast 20 thereof having an inclined-bottom recess for the reception of the rear end of an outsole.

Signed at Bristol, Rhode Island, this 10th day of January, 1921.

EUGENE C. HEILHECKER.
